UNITED STATES PATENT OFFICE.

FREDERICK S. JAINETT, OF PRESIDIO, CALIFORNIA.

RAIL FASTENER AND SUPPORT.

1,129,397.

Specification of Letters Patent. Patented Feb. 23, 1915.

Application filed December 10, 1912. Serial No. 805,784.

To all whom it may concern:

Be it known that I, FREDERICK S. JAINETT, citizen of the United States, residing at Presidio, in the county of San Francisco and State of California, have invented certain new and useful Improvements in Rail Fasteners and Supports, of which the following is a specification.

This invention relates to improvements in railway rail fasteners and supports, and has for one of its objects to improve the construction and increase the efficiency and utility of devices of this character.

Another object of the invention is to provide a simply constructed fastening device which requires no change in the rails or the ties, and whereby the rails are firmly supported and held at the joints and prevented from movement laterally of the roadbed, whereby the spreading of the rails is effectually prevented.

With these and other objects in view the invention consists in certain novel features of construction as hereinafter shown and described and then specifically pointed out in the claims, and in the drawings illustrative of the preferred embodiment of the invention.

Figure 1 is a plan view of the improved device. Fig. 2 is an end elevation with the rail in section on the line 2—2 of Fig. 1.

Corresponding and like parts are referred to in the following description and indicated in all the views of the drawings by the same reference characters.

The improved device comprises a base plate 10 bearing upon a pair of ties 11 and clamped firmly to the ties by bolts or like fastening devices 12 and clamp plates 13. Any required number of the bolts may be employed, but preferably arranged upon opposite sides of the ties 11, as shown. The rails, represented conventionally at 14, bear upon the plate near one edge and with their abutting ends about centrally of the plate. A clamp member 15 is formed integrally with the base plate to bear upon the flanges of the rails and includes a vertical web 17 which bears against the webs of the rails and beneath the heads of the same. Bearing upon the plate 10 at the opposite side of the rail from the clamp member 15 is another clamp 18 having a vertical web 19 bearing against the opposite side of and beneath the heads of the rails. The member 18 extends for some distance over the upper face of the

plate 10 and is formed with a vertical flange or web 20. The member 18 is secured in position upon the plate 10 by clamp bolts or like devices 21, the bolts extending through slots 22 in the plate 10 and being provided with heads 23 at their lower ends which bear beneath the base plate. By this means the member 18 may be adjusted as hereafter explained, and then clamped in position by actuating the nuts of the bolts 21.

Formed upon the plate 10 is an abutment or web 24, preferably integral with the base plate and through which a pressure applying member 25 is threaded and bears against the web 20 of the member 18. At its outer end the member 25 is provided with a wrench receiving head 26. Any required number of the members 25 may be employed, but generally one will be sufficient as shown. By this means it will be obvious that the member 18 may be forced against the rails 14 by actuating the threaded member 25, to firmly unite the parts and clamp them together, and when this adjustment has been secured the member 18 may be firmly locked in position by actuating the nuts of the bolts 21, thus relieving the member 25 largely from strain. The fastening devices 21 likewise hold the member 18 in its downward position in engagement with the base 10, and prevent all displacement under the severe strains to which devices of this character are subjected. It is to be noted also that with my construction the rail engaging member 18 may be removed to permit the insertion of a new rail without removing the bedplate itself, and it will also be noted that the rail engaging member 18 is vertically movable with relation to the bedplate and with relation to the screw 25.

If preferred a boss or enlargement 27 may be formed upon the web 24 to increase the length of the bearings for the threaded member 25. Additional fastening devices 100 are likewise employed for preventing the spreading of the rails and consisting of rods 28 and hooked terminals 29 for engaging over the outer edges of the plate 10 of the member 15 and with spiked terminals 31 105 adapted to be driven into the material of the tie to hold the member 28 in position. By this means the spreading of the rail is effectually prevented. Any required number of the members 28 may be employed, and it 110 is not desired to limit the invention in this respect.

The improved device is simple in construction; can be inexpensively manufactured and applied, and does not require any change in the rails to apply the improved fastening device.

Having thus described the invention, what is claimed as new is:

1. A railway rail fastener comprising a tie engaging member to receive the rail ends and having a rigid rail brace rising therefrom and adapted to engage the rail ends at one side, said rail engaging member having elongated apertures spaced apart, a rigid support rising from the tie engaging member and having a threaded aperture intermediate the ends, a movable rail brace bearing upon the tie engaging member and having bolt receiving apertures constantly registering with the elongated apertures of the tie engaging member, clamp bolts engaging through the apertures and slots and operating to guide the movable rail brace and clamp the same to the tie engaging member, and a threaded straining member engaging the intermediate threaded aperture of the support and bearing against the movable rail brace between the combined clamping and guiding members.
2. A railway rail fastener comprising a tie engaging member to receive the rail ends and having a rigid rail brace rising there-

from and adapted to engage the rail ends at one side, a rigid support rising from the tie engaging member and having a threaded aperture intermediate the ends, a movable rail brace bearing upon the tie engaging member and having bolt receiving apertures constantly registering with the elongated apertures of the tie engaging member, said movable rail brace having a reinforcing rib at its outer edge, clamp bolts engaging through the apertures and slots and operating to guide the movable rail brace, and clamp the same to the tie engaging member, and a threaded straining member engaging the intermediate threaded apertures of the support and bearing against the reinforcing rib.

3. In a rail support, a bedplate having an upstanding abutment, a rail engaging member disposed upon the bedplate and having an upstanding flange extending parallel to the abutment, a screw passing through the abutment and engaging the upstanding flange, and means for detachably holding the rail engaging member to the bedplate.

In testimony whereof I affix my signature in presence of two witnesses.

FREDERICK S. JAINETT. [L. S.]
